UNITED STATES PATENT OFFICE.

MARY F. POSTLEY, OF NEW YORK, N. Y.

DESIGN FOR A CORN-HOLDER.

SPECIFICATION forming part of Design No. 25,025, dated December 31, 1895.

Application filed September 7, 1895. Serial No. 561,866. Term of patent 7 years.

To all whom it may concern:

Be it known that I, MARY F. POSTLEY, a citizen of the United States, residing at the city of New York, in the county of New York and State of New York, have invented and produced a new and original Design for a Corn-Holder, of which the following is a specification, reference being had to the accompanying drawings, forming part thereof, which show, in—

Figure 1, the obverse and in Fig. 2 the reverse of my corn-holder in perspective.

My new and original design for a corn-holder comprises a device of this character, and the leading feature of my design consists in a handle A, which is substantially cylindrical in form, the outer end of which is tapered to a point and the inner portion of which is contracted at C, and upon which is mounted a cross-head D, having inwardly-directed wings or shoulders E, the inner sides of which are ornamented, as shown in the drawings, and projecting centrally from said cross-head is a prong F, all substantially as shown in the drawings, and upon the handle A is an ornamental inclined band G, and these ornamental bands begin at the inner portion of the handle A and extend around the handle outwardly, as shown, and it will thus be seen that my design is harmonious in form and outline and presents a pleasing appearance to the eye.

Having fully described my invention, I claim and desire to secure by Letters Patent—

The design for a corn holder herein shown and described.

In testimony that I claim the foregoing as my invention I have signed my name, in the presence of the subscribing witnesses, this 5th day of September, 1895.

MARY F. POSTLEY.
